CIRCUMCISION CLAMP

John J. Turner, Highland Park, Mich.

Continuation of application Serial No. 727,013,
February 7, 1947. This application October 29,
1949, Serial No. 124,352

9 Claims. (Cl. 128—346)

1

My invention relates to a new and useful improvement in a surgical instrument adapted for use particularly in circumcising.

This application constitutes a continuation of my application Serial Number 727,103 filed February 7, 1947, now abandoned.

It is an object of the present invention to provide in instruments of this class whereby a surgeon may easily and quickly clamp the foreskin in position for performing the operation.

Another object of the invention is the provision of a device of this class whereby the foreskin will remain clamped after the operation to prevent excessive bleeding.

Another object of the invention is the provision of a clamping mechanism in a device of this class which may be easily and quickly moved into position for clamping the foreskin after the proper adjustments of the instrument with the foreskin located thereon have been made and whereby the clamp having the foreskin located thereon is held to prevent rotation.

Another object of the invention is the provision of a device of this class which will be simple in structure, economical of manufacture, durable, light, compact, and easily and quickly operated.

Other objects will appear hereinafter.

It is recognized that various modifications and changes may be made in the detail of structure illustrated without departing from the invention itself and it is intended that such shall be embraced within the scope of the claims which form a part hereof.

Forming a part of this specification are drawings in which:

Fig. 1 is a top plan view of the invention.

Fig. 2 is a side elevational view of the invention with parts broken away and parts shown in section.

Fig. 3 is an enlarged cross-sectional view taken on line 3—3 of Fig. 2.

Fig. 4 is a sectional view taken on line 4—4 of Fig. 3.

Fig. 5 is a sectional view taken on line 5—5 of Fig. 3.

Fig. 6 is a side elevational view of the invention in collapsed form and slightly reduced in size.

As shown in the drawings, the invention comprises a base 12 projecting diametrically outwardly from which at opposite sides thereof are the arms 13 and 14 whose ends are turned upwardly as at 15. The base 12 is formed circular and has a threaded hole 16 therethrough. Adapted to seat upon the face of the base 12 is a disc

2

18 having the downwardly extended neck 17 for threading into the threaded hole 16. A tapered opening 19 is formed through the neck 17. At the narrowest diameter of the opening 19 the sides flare outwardly to provide a seat 20 on the face of the disc 18.

Legs 21 and 21a are pivotally secured at one of their ends to the up-turned ends 15 by means of a screw 21b. The opposite ends of these legs 21 and 21a are connected by the cross-head 23. Fixedly secured in the cross-head 23 is a sleeve 24. Threaded through the sleeve 24 is a screw 25 having the knurled knob 26 on its upper end and provided on its lower end with the cavity 27 in which the end of the clamping rod 28 may engage. The lower end of the rod 28 is flared outwardly, as at 29, to form a head about which the foreskin 31 is drawn upwardly to embrace the lower end of the rod 28. The rod 28 is provided with a passage 32 which communicates with the lateral passage 33 which, in turn, communicates with the recess 34 formed in the end of the rod. The rod 28 is provided with flat sides 35 adapted to engage in the pocket 36 formed in the cross-member 37 which is secured between and to the legs 21 and 21a.

Pivotedly secured by screws 38 adjacent the upper end of the legs 21 and 21a are the arms 39 and 40 of the channel link 41. The end of the channel link 41 is pivotally connected by pin 43 to one end of the toggle link 42, its opposite end connected by pin 44 to the lugs 45 secured on the plate 46 that extends rearwardly of the arms 13 and 14. Carried by the channel link 41 is the pin 48 against which is adapted to rest the band 47 which, when moved against the pin 48, serves to lock the toggle link 42 with the channel link 41 against pivotal movement.

In the use of the instrument, the legs 21 and 21a would be moved to the position shown in Fig. 6. The surgeon would then draw the foreskin 31 through the opening 19 so as to embrace the lower end of the rod 28 which would be seated upon the seat 20 so that the foreskin is pressed by the end 30 against the edges of the opening. The legs 21 and 21a would then be swung upwardly and the toggle links 41 and 42 when straightened out and locked in alignment by the band 47 would locate the head 23 directly over the upper end of the rod 28. As the legs 21 and 21a are swung upwardly, the rod 28 would enter into the pocket 36 to further locate its alignment with the screw 25. The flat sides 35 of the rod engaging the straight sides of the pocket 36 will prevent the rod from rotating

as the surgeon, upon rotating the screw 25, would force the rod 28 downwardly so as to tightly clamp the foreskin between the end 30 and the seat 20. By holding the rod 28 against rotation, the foreskin 31 will not become displaced on the stem nor twisted thereon. The cutting instrument is rested upon the face of the disc and brought into contact with the foreskin to effect the necessary severing, as the foreskin is not twisted or bunched, there will be effected a clean, even cutting. After the circumcision has been effected the remaining foreskin would still remain clamped tightly by the end of the rod 28 upon the seat 20 so that bleeding would be practically eliminated. After the operation, the surgeon would unthread the screw 25 until the stem 28 was disengaged whereupon the structure may be collapsed into the position shown in Fig. 6, and the rod 28 easily removed.

Experience has shown that with a clamping device of this type, the operation may be quickly and easily performed in a most efficient manner with a minimum amount of bleeding. Experience has also shown that by having the parts swingably connected, as indicated, the operator, when beginning the operation, may move quickly as all of the parts are ready for movement into operative position.

Further, by having the disc 18 threadably attached into the base 12 it can easily and readily be changed with a disc having a larger or smaller diameter bore 19 so that the device is quickly altered and readied for use to provide the proper and requisite bore diameter necessary for drawing the foreskin of a person to be circumcised. This disc 18 may be said to be a presser plate which is detachably mounted in the threaded opening of the base.

What I claim is:

1. A device of the class described comprising: a base having an opening extended therethrough; legs pivotally mounted at one of their ends to said base in diametrically opposed relation to said opening, the opposite ends of said legs being joined by a cross head; a rod having a head adapted for seating over said opening for clamping thereagainst the foreskin of a person drawn onto said rod; rotatable means carried by said cross head for engagement with said rod for exerting pressure on said rod longitudinally thereof for pressing said head towards said opening; locking means carried by said legs for locking said rod against rotation; and toggle links connected between said base and said legs adjacent said cross head and pivotally connected together for moving into alignment for effecting a swinging of said legs into axial alignment with said opening.

2. A device of the class described, comprising: a base having an opening extended therethrough; legs pivotally mounted at one of their ends to said base in diametrically opposed relation to said opening, the opposite ends of said legs being joined by a cross head; a rod having a head adapted for seating over said opening for clamping thereagainst the foreskin of a person drawn onto said rod; rotatable means carried by said cross head for engagement with said rod for exerting pressure on said rod longitudinally thereof for pressing said head towards said opening; locking means carried by said legs for locking said rod against rotation; and toggle links connected between said base and said legs adjacent said cross head and pivotally connected together for moving into alignment for effecting a swinging of said legs into axial alignment with said opening.

swinging of said legs into axial alignment with said opening, and a collar movable on said links for locking said links to prevent their pivotal movement relative to each other.

3. A device of the class described comprising: a base having an opening extended therethrough; a disc having a neck extended into said opening for securing said disc to said base, there being an opening extended through said disc and neck, a seat formed about said opening on the face of said disc; legs pivotally at one of their ends to said base in diametrically opposed relation to said disc, the opposite ends of said legs being joined by a cross head; a rod having a head, the end of said head being formed for seating on said seat for clamping thereagainst the foreskin of a person drawn onto said rod; rotatable means carried by said cross head for engagement with said rod for exerting pressure on said rod longitudinally thereof for pressing said head towards said opening; locking means carried by said legs for locking said rod against rotation; and toggle links connected between said base and said legs adjacent said cross head and pivotally connected together for moving into alignment for effecting a swinging of said legs into axial alignment with said opening.

4. A device of the class described comprising: a base having an opening extended therethrough; a disc having a neck extended into said opening for securing said disc to said base, there being an opening extended through said disc and neck, a seat formed about said opening on face of said disc; legs pivotally mounted at one of their ends to said base in diametrically opposed relation to said disc, the opposite ends of said legs being joined by a cross head; a rod having a head, the end of said head being formed for seating on said seat for clamping thereagainst the foreskin of a person drawn onto said rod; rotatable means carried by said cross head for engagement with said rod for exerting pressure on said rod longitudinally thereof for pressing said head towards said opening; locking means carried by said legs for locking said rod against rotation; toggle links connected between said base and said legs adjacent said cross head and pivotally connected together for moving into alignment for effecting a swinging of said legs into axial alignment with said opening, and a collar movable on said links for locking said links to prevent their pivotal movement relative to each other.

5. A device of the class described, comprising: a base having an opening extended therethrough; a disc extended into said opening and having a portion thereof above the upper face of said opening, there being an opening extended through said disc; a seat formed about said opening at the upper face of said disc; a rod having a head, the end of said head being formed for seating on said seat for clamping thereagainst the foreskin of a person drawn onto said rod; and a presser member for exerting pressure longitudinally of said rod for effecting said clamping, said disc being detachable from said base.

6. In a surgical instrument for circumcising, a base having an opening formed therethrough; a presser plate overlying said base around said opening and detachably mounted on said base and having an opening formed therethrough concentric with the opening in said base; a presser rod; a head on said presser rod for engaging the foreskin of a person, after said foreskin has been drawn through said opening, and

pressing the same against said plate around said opening; and a clamping structure mounted on said base and operable for exerting pressure on said rod longitudinally thereof for forcing said head against said plate.

7. In a surgical instrument for circumcising, a base having an opening formed therethrough; a disc; a neck extending concentrically, outwardly from one face of said disc for engaging in said opening and detachably mounting said disc on said base; an opening extending concentrically through said neck and tapering to smaller diameter approaching said disc, said opening, at the end opening through said disc, being chamfered to provide a seat, the upper face of said disc being of conical formation; a support extending upwardly from said base; a rod; a head on said rod having its end formed to seat on said seat and clamping the foreskin of a person, after the foreskin has been drawn through said opening, against said seat; and a pressure exerting member of said support for engaging said rod and forcing said head into said clamping relation.

8. In a surgical instrument for circumcising, a base having an opening formed therethrough; a disc; a neck extending concentrically, outwardly from one face of said disc for engaging in said opening and detachably mounting said disc on said base; an opening extending concentrically through said neck and tapering to smaller diameter approaching said disc, said opening, at the end opening through said disc, being chamfered to provide a seat, the upper face of said disc being of conical formation; a support

25

extending upwardly from said base; a rod; a head on said rod having its end formed to seat on said seat and clamping the foreskin of a person, after the foreskin has been drawn through said opening, against said seat; and a pressure exerting member on said support for engaging said rod and forcing said head into said clamping relation; and an engaging portion on said support for engaging and preventing a rotation of said rod.

9. In a surgical instrument for circumcising, a base having an opening formed therethrough; a plate detachably mounted on said base and having an opening formed therethrough concentric with the opening in said base, said opening being chamfered at opposite face of said plate, the chamfered portion of said plate forming a seat; a rod, one end of said rod being adapted for bearing against said seat for clamping thereagainst the foreskin of a person drawn through said opening; and a pressure exerting mechanism for exerting pressure on said rod for effecting said clamping.
